(57) **ABSTRACT**

A shipping vessel including a train for executing underwater travel is disclosed. The train is formed by a plurality of segments hingedly coupled to one another in a series. Each segment includes one or more variable ballast tanks and one or more hydrodynamic features. The shipping vessel includes a control system configured to cause the one or more variable ballast tanks of the plurality of segments to be selectively filled with and expelled of a fluid to correspondingly change buoyancies of the plurality of segments. The control system is configured to control the one or more hydrodynamic features in each segment to translate an underwater downward acceleration and the underwater upward acceleration into a desired direction as at least one of pitch and yaw. Thus, executing a glide maneuver to glide up and down underwater among the train of the plurality of segments and along a glide path.

**VARIABLE BALLAST PROPULSION
SHIPPING VESSEL, SYSTEMS AND
METHODS**

**CROSS REFERENCE TO RELATED
APPLICATIONS**

This present application is a Continuation Application of and claims the benefit of U.S. patent application Ser. No. 18/834,219, entitled “VARIABLE BALLAST PROPULSION SHIPPING VESSEL, SYSTEMS AND METHODS”, filed Jul. 29, 2024, which application claims the benefit of International Application No. PCT/US2023/037256, entitled “VARIABLE BALLAST PROPULSION SHIPPING VESSEL, SYSTEMS AND METHODS”, filed Nov. 14, 2023, which applications are incorporated herein by reference in their entirety.

FIELD OF THE INVENTION

The present invention relates generally to ocean freight shipping technology. More particularly, this invention pertains to assemblies, systems, and methods for maritime autonomous cargo shipping in both surfaced and submerged modes.

BACKGROUND OF THE INVENTION

Approximately 80 percent of goods constituting global trade are transported by ocean shipping, most carried inside 40-foot-long steel containers stacked by the thousands atop some of the largest vessels in the world. Between 1990 and 2021, the volume of cargo transported by ships grew from 4 billion tons to nearly 11 billion tons. Nearly 69 percent of all the goods traded by the United States of America are transported via waterways, predominantly by seagoing vessels. Ships transport over 41 percent of the total value of goods traded by the United States.

The supply chain delays caused by the coronavirus pandemic underscored both how crucial the maritime container trade is to the global economy, and how vulnerable ocean shipping is to catastrophic disruption. Pandemic-driven challenges caused the cost of shipping a container on the world's transoceanic trade routes to increase seven-fold in the 18 months following March 2020, while the cost of shipping bulk commodities spiked even more. Ship chartering costs surged by up to 773% since late May 2020. Marine fuel costs near tripled from \$155.5 per metric ton in April 2020 to \$435.5 per metric ton currently. The one-day cost of operating a 4,250-box ship spiked during that time from about \$30,200 per day in mid-June 2020 to about \$151,400 a day currently.

Ocean shipping at such a large scale has significant environmental impact, are responsible for more than 18 percent of certain air pollutants, including greenhouse gas emissions. The International Maritime Organization (IMO) estimates that carbon dioxide emissions from shipping were equal to 2.2% of the global human-made emissions in 2012 and expects such including air pollution, water pollution, acoustic noise, and oil pollution. Ships 30 emissions to rise 50 to 250 percent by 2050 if no action is taken.

What is needed are alternative systems and methods for timely, reliable, and affordable delivery of bulk freight and/or goods containers via ocean shipping. Specifically, ocean-going vessel designs that produce little or no hydrocarbons and, ideally, that do not use fossil fuels for propulsion are desired. Besides being more environmentally

2

friendly, employment of engines that do not burn fossil fuels holds promise for propulsion means that are less expensive to build, maintain, and/or repair than legacy engine technologies. Vessel designs with the advantage of autonomous control may be deployed without a manned crew, further lowering operating costs and eliminating human error. Vessel designs that support submerged mode operation may provide a safer method of transporting cargo across oceans due to natural protection from surface storms and high seas.

This background information is provided to reveal information believed by the applicant to be of possible relevance to the present invention. No admission is necessarily intended, nor should be construed, that any of the preceding information constitutes prior art against the present invention.

SUMMARY OF THE INVENTION

20 In one aspect, a shipping vessel is disclosed. The shipping vessel includes a train for executing underwater travel. The train may be formed by a plurality of segments hingedly coupled to one another in a series. Each segment of the plurality of segments includes one or more variable ballast tanks and one or more hydrodynamic features. The shipping vessel further includes a control system configured to cause the one or more variable ballast tanks of the plurality of segments to be selectively filled with and expelled of a fluid to correspondingly change buoyancies of the plurality of segments. Accordingly, a filling of fluid into each segment causes an underwater downward acceleration of the corresponding segment and an expulsion of fluid from the segment causes an underwater upward acceleration of the corresponding segment. The control system is configured to 30 control the one or more hydrodynamic features in each segment to translate the underwater downward acceleration and the underwater upward acceleration into a desired direction as at least one of pitch and yaw. Such that the shipping vessel is configured to execute a glide maneuver to 35 control up and down underwater among the train of the plurality of segments and along a glide path defined by a series of peaks and troughs to move the shipping vessel underwater.

In another aspect, a method for executing underwater travel is disclosed. The method includes using a shipping vessel including a train formed by a plurality of segments hingedly coupled to one another in a series, each segment of the plurality of segments including one or more variable ballast tanks and one or more hydrodynamic features. The method includes causing, by a control system, the one or more variable ballast tanks of the plurality of segments to be selectively filled with and expelled of a fluid to correspondingly change buoyancies of the plurality of segments by the control system, wherein a filling of fluid into each segment 45 causes an underwater downward acceleration of the corresponding segment and an expulsion of fluid from the segment causes an underwater upward acceleration of the corresponding segment. The method includes controlling, by the control system, the one or more hydrodynamic features in each segment to translate the underwater downward acceleration and the underwater upward acceleration into a desired direction as at least one of pitch and yaw by the control system, such that the shipping vessel executes a 50 glide maneuver to glide up and down underwater among the train of the plurality of segments and along a glide path defined by a series of peaks and troughs to move the shipping vessel underwater.

These and other objects, features, and advantages of the present invention will become more readily apparent from the attached drawings and the detailed description of the preferred embodiments, which follow.

BRIEF DESCRIPTION OF THE DRAWINGS

The preferred embodiments of the invention will herein-after be described in conjunction with the appended drawings provided to illustrate and not to limit the invention, where like designations denote like elements, and in which:

FIG. 1 is a side elevation view schematic diagram of a variable ballast propulsion shipping vessel according to an embodiment of the present invention;

FIG. 2 is a side elevation view schematic diagram of an exemplary lead segment of the variable ballast propulsion shipping vessel of FIG. 1;

FIG. 3 is a front elevation cross-section view schematic diagram of the exemplary lead segment of FIG. 2 as viewed through line A-A;

FIG. 4 is a top elevation view schematic diagram of the exemplary lead segment of FIG. 2 with wings deployed;

FIG. 5 is a top elevation view schematic diagram of the exemplary lead segment of FIG. 2 with starboard wings retracted;

FIG. 6 is a side elevation view schematic diagram of an exemplary cargo segment of the variable ballast propulsion shipping vessel of FIG. 1;

FIG. 7 is a front elevation cross-section view schematic diagram of the exemplary cargo segment of FIG. 6 as viewed through line B-B;

FIG. 8 is a top elevation view schematic diagram of the exemplary cargo segment of FIG. 6;

FIG. 9 is a top elevation view schematic diagram of a tail segment of the variable ballast propulsion shipping vessel of FIG. 1;

FIG. 10 is a block diagram of a variable ballast propulsion shipping vessel control system according to an embodiment of the present invention;

FIG. 11 is a flowchart of exemplary computer-implemented logic for a Navigation Subsystem of the variable ballast propulsion shipping vessel control system of FIG. 8;

FIG. 12 is a flowchart of exemplary computer-implemented logic for a Train Glide Subsystem of the variable ballast propulsion shipping vessel control system of FIG. 8;

FIG. 13 is a flowchart of exemplary computer-implemented logic for a Segment Drive Subsystem of the variable ballast propulsion shipping vessel control system of FIG. 8;

FIG. 14 is a side elevation view schematic diagram of an exemplary slipstream adornment of the lead segment of FIG. 2;

FIG. 15 is a side elevation view schematic diagram of an exemplary slipstream adornment of the cargo segment of FIG. 5 with starboard wing folded; and

FIG. 16 is a side elevation view schematic diagram of an exemplary slipstream adornment of the variable ballast propulsion shipping vessel of FIG. 1.

As used herein, like reference numerals refer to like parts throughout the several views of the drawings.

forms and should not be construed as limited to the embodiments set forth herein. Rather, these embodiments are provided so that this disclosure will be thorough and complete, and will fully convey the scope of the invention to those skilled in the art.

Although the following detailed description contains many specifics for the purposes of illustration, anyone of ordinary skill in the art will appreciate that many variations and alterations to the following details are within the scope 10 of the invention. Accordingly, the following embodiments of the invention are set forth without any loss of generality to, and without imposing limitations upon, the claimed invention.

As used herein, the word "exemplary" or "illustrative" 15 means "serving as an example, instance, or illustration." Any implementation described herein as "exemplary" or "illustrative" is not necessarily to be construed as preferred or advantageous over other implementations. All of the implementations described below are exemplary implementations 20 provided to enable persons skilled in the art to make or use the embodiments of the disclosure and are not intended to limit the scope of the disclosure, which is defined by the claims.

Furthermore, in this detailed description, a person skilled 25 in the art should note that quantitative qualifying terms such as "generally," "substantially," "mostly," and other terms are used, in general, to mean that the referred to object, characteristic, or quality constitutes a majority of the subject of the reference. The meaning of any of these terms is dependent upon the context within which it is used, and the meaning may be expressly modified.

In general, the present invention relates to a variable ballast propulsion submersible vessel for transporting removable cargo (e.g., fluid or dry bulk freight, goods in 30 shipping containers). The submersible may comprise substantially identical water-tight, cargo-carrying segments connected sequentially by respective mating hinge mechanisms. Each segment may be selectively attached and detached from the next adjacent segment, allowing variable length "trains" to be assembled and moved by water in both submerged and surfaced modes.

Each cargo segment may be largely a slave to external control by a detachable bow- and/or stern-based computerized control system (e.g., an onboard computer, local area 45 network, and long-haul communication link to a remote navigation system; alternatively, an onboard computer and stored navigation data and undersea topographical maps, to govern navigation along a pre-recorded sail plan; also alternatively, an on-board computer monitoring onboard environmental sensors and executing real-time autonomous navigation rules (e.g., artificial intelligence) to determine and execute a non-recorded sail plan).

In certain embodiments, the assembled vessel may be 50 designed to operate at depths from 3 to 20,000 feet while underway for long-haul navigation. At both the beginning and end of a delivery "sortie", the assembled vessel may operate in surfaced mode in and around a port area, optionally assisted by one or more local port-based service vessels capable of towing assembled (e.g., "trains") and/or individual sections of the vessel segments loaded with cargo. As the segments are quickly unloaded and reloaded, they may be reattached as part of a train supporting another delivery sortie. The port-based service vessel(s) may tow assembled segments from an origination port area back out to sea where the reloaded vessel may then be sent on its way to the next required delivery destination. One cargo-carrying segment operated by a lead segment (e.g., by the onboard control

DETAILED DESCRIPTION OF THE INVENTION

The present invention will now be described more fully hereinafter with reference to the accompanying drawings, in which preferred embodiments of the invention are shown. This invention may, however, be embodied in many different

system) may be a theoretical minimum number of segments required for certain embodiments of the present invention to operate (e.g., to create variable buoyancy motion).

Variable ballast propulsion may be defined as the bow- and/or stern-based computer-based control system coordinating oscillation of the respective ballasts present in each cargo segment of an assembled train of cargo segments. The timing of electrically triggered ballast intake and exhaust ports onboard each cargo segment may create an underwater gliding up and down motion among the train of cargo segments. The control system may similarly operate directional components present on the external structure of each cargo segment in the train. Such components may translate the simple up and down motion created by a given cargo segment into pitch (e.g., planes actuating from paired, side-mounted wings) and/or yaw (e.g., a rudder actuating from a dorsal wing).

More specifically, computer-based control system may cause water to enter a ballast tank of a given segment, creating negative buoyancy. Now in a negative buoyancy state, the segment may descend on a glide path to a predetermined depth before the computer-based control system may suddenly cause air to be pumped into the ballast tank of the segment to change the buoyancy state to positive. Behaving much like a glider, the computer-based control system may electrically trigger the aerodynamic features (e.g., planes, rudders) of each cargo segment to exploit both its negative and positive buoyancy states by translating the either downward or upward acceleration into a desired direction (as a combination of pitch and/or yaw). Emergency system failures may be dealt with by a depth sensor that may trigger airbags to be deployed past a certain depth and/or when desired forward motion is somehow lost.

In certain embodiments, the minimal power source onboard a given cargo segment to operate the variably buoyancy propulsion "engine" is an electric battery that may be recharged while the segment is underway, for example, using impellers mounted on the respective sides/top of each segment and electrically connected to small battery chargers (e.g., alternators). Designs that use battery power to manipulate ballast equipment onboard individual segments may advantageously result in a vessel that uses less hydrocarbons than legacy container ships. Battery-stored electrical power on each segment alternatively may be replenished by optional onboard charging systems such as solar panels (e.g., when a vessel is surfaced), water or wind turbine chargers (e.g., when moving underwater or when surfaced in moving air), and/or inverter/charger (e.g., when connected to shore power).

Without the need for fossil fuels for propulsion, the present shipping design may be much more environmentally friendly than traditional shipping options. Without the need for engines burning fossil fuels, the need for expensive and reoccurring maintenance and/or repairs of engines and equipment may advantageously be reduced. The vessel described herein may be autonomous and requires no crew, further lowering costs, and may be a vastly safer method of transporting cargo across oceans and seas due to the submersible capabilities of the vessel (i.e., no need to contend with storms and surface waves, with reefs and obstructions, and/or with shallow water).

Referring initially to FIG. 1, a variable ballast propulsion shipping vessel 100 according to an embodiment of the present invention will now be described in detail. In the exemplary configuration of FIG. 1, the shipping vessel 100 may comprise a lead segment 102 mechanically attached to a first of some number of cargo segments 104 which are

mechanically attached to each other, in series, before ending with a mechanically attached tail segment 106.

Still referring to FIG. 1, and referring additionally to FIG. 2, the lead segment 102 may be characterized by a superstructure comprising a nose cone 202 (i.e., defining a bow) mounted forward of a lead body portion 203. A fixed ballast 206 may be mounted to a bottom of the lead body portion 203, for example, and without limitation, to maintain stability of the lead segment 102 when operating both in submerged and surfaced modes. An aft hinge mechanism 212 may be mounted to the lead body portion 203 opposite the nose cone 202, for example, and without limitation, to facilitate mechanical attachment to an assembled "train" of vessel segments 104, 106 to be operated by the lead segment 102.

Still referring to FIG. 2, and referring additionally to FIGS. 3, 4 and 5, the lead segment 102 may further comprise some number of port and starboard glide wings 220 configured to project paired and laterally (with respect to a centerline) from the lead body portion 203. The exemplary embodiment illustrated in FIGS. 2, 3, 4 and 5 comprises two pairs of glide wings 220 (four wings total). Those skilled in the art will readily appreciate that lead segment 102 designs, as well as cargo segment 104 designs described hereinbelow, may comprise a single pair of wings, or three (3) or more pairs of wings, while still accomplishing the many goals, features and advantages according to the present disclosure.

As illustrated in FIG. 3, each of the glide wings 220 may present a respective substantially flat bottom surface which may augment a substantially flat bottom of the fixed ballast 206 to present a hydrodynamic glide effect when the lead segment 102 is underway, and particularly in submerged mode. Each glide wing 220 may include at least one plane 222 that may be operated in combination with the wing planes 222 of the other glide wings 220 deployed, for example, and without limitation, to control lead segment 102 pitch and, with forward motion, to control lead segment 102 depth. Additionally, a dorsal wing 240 having a rudder 242 may be mounted to a top of the lead body portion 203, for example, and without limitation, to provide a primary control surface for selectively steering the lead segment 102 generally to port and/or to starboard.

Various accessories mounted on an exterior of lead segment 102 each may be configured as watertight assemblies to prevent water intrusion. For example, and without limitation, a navigation light 230 may be mounted at the bow of nose cone 202 for use as a safety beacon during night or reduced visibility navigation. Also, for example, and without limitation, environmental profiling gear 201 (e.g., instruments for measuring temperature, salinity, and/or pressure) may be mounted external to the nose cone 202 and/or to the lead body portion 203. Also, for example, and without limitation, a networking cable with plug 232 may be mounted at the stern of the lead body portion 203 for use in delivery of electric power and/or communication signals to "train" vessel segments 104, 106, as described in more detail hereinbelow. The lead segment 102 may further comprise an access panel 207 that may be opened when the lead segment 102 is in surfaced mode or when dry docked to allow maintenance access to components and systems that may be deployed either partially or fully inside the superstructure 202, 203 of the lead segment 102. For example, and without limitation, some number of impellers 208 may be configured to partially project from the exterior of lead segment 102 to translate movement of the lead segment 102 in submerged mode into spinning of the impeller(s) that, in turn, may be

converted by a battery charger 310 into electrical current for power storage into an onboard battery bank 312.

The battery bank 312 may be used to power various substantially mechanical onboard systems including motors (not shown) used to actuate the planes 222 of the glide wings 220, and/or rudder(s) 242 of the dorsal wing(s) 240. Other substantially mechanical onboard systems powered by the battery bank 312 may include ballast intake(s)/exhaust(s) 302 used to selectively receive or expel water into/out of a variable ballast tank(s) 304; an air compressor 305 used to fill a compressed air tank 306 from which air may be introduced into the variable ballast tank(s) 304 to expel water for purposes of changing buoyancy of the lead segment 102; and a motor (not shown) used to actuate retractable and/or stowable components such as a global positioning system (GPS) antenna 210, the glide wings 220 (showing starboard wings retracted in FIG. 5), and/or the dorsal wing 240. The battery bank 312 also may be used to power shipping vessel control system 320 components and electronic devices (e.g., on-board computer; local area networking, long-haul communications, onboard sensors).

Referring now to FIGS. 6, 7 and 8, each cargo segment 104 may be characterized by a superstructure comprising a cargo body portion 403 that may include at least one sealable access mechanism. For example, and without limitation, a cargo door 404 may be configured for top loading/unloading of cargo organized into containers shaped to substantially fit an interior cargo bay 455 of the cargo body portion 403. Also for example, and without limitation, a hatch 405 and/or a capped filler neck 407 may be configured for fill and/or retrieval of loose bulk cargo (e.g., grain, sand, gravel) and/or fluid cargo (e.g., oil, gas) to/from any number of advantageously arranged onboard cargo tanks 455. A person of skill in the art will immediately recognize that an advantageous implementation of needed sealable access mechanisms may be bottom-mounted (e.g., for gravity drain) rather than and/or in addition to top-mounted on the cargo body portion 403.

A fixed ballast 406 may be mounted to a bottom of the cargo body portion 403, for example, and without limitation, to maintain stability of the cargo segment 104 when operating both in submerged and surfaced modes. A forward hinge mechanism 410 and an aft hinge mechanism 412 may be mounted to a bow and a stern, respectively, of the cargo body portion 403, for example, and without limitation, to facilitate mechanical attachment in line as part of the assembled “train” of vessel segments 104, 106 as operated by the lead segment 102. Each cargo segment 104 may further comprise some number of port and starboard glide wings 420 configured to project pairedly and laterally (with respect to a centerline) from the cargo body portion 403. Each of the glide wings 420 may present a respective substantially flat bottom surface which may augment a substantially flat bottom of the fixed ballast 406 to present a hydrodynamic glide effect when the cargo segment 104 is underway in submerged mode. Each glide wing 420 may include at least one plane 422 that may be operated in combination with the wing plane(s) 422 of the other glide wing(s) 420 deployed, for example, and without limitation, to control cargo segment 104 pitch and, with forward motion, to control cargo segment 104 depth. Additionally, a dorsal wing 440 having a rudder 442 may be mounted to a top of the cargo body portion 403, for example, and without limitation, to provide a primary control surface for selectively steering the cargo segment 104 generally to port and/or to starboard.

Various accessories mounted on an exterior of cargo segment 104 each may be configured as watertight assemblies to prevent water intrusion. For example, and without limitation, a networking cable receptacle 430 may be mounted forward on the cargo body portion 103; and a networking cable with plug 432 may be mounted at the stern of the cargo body portion 403. A reconfigurable bus for delivery of electric power and/or communication signals from lead segment 102 to a “train” of cargo segments 104 may be formed by using each networking cable receptacle 430 to fittedly receive the respective networking cable with plug 432 of the adjacent vessel segment 102, 104 in the assembled “train.”

Each cargo segment 104 may further comprise components and systems that may be deployed either partially or fully inside the cargo body portion 403 of cargo segment 104. For example, and without limitation, some number of impellers 408 may be configured to partially project from the exterior of cargo segment 104 to translate movement of the cargo segment 104 in submerged mode into spinning of the impeller(s) 408. Similar to the description above for the lead segment 102, the spinning of the impeller(s) 408, in turn, may be converted by a battery charger 510 into electrical current for power storage into an onboard battery bank 512. This battery bank may be used to power various substantially mechanical systems onboard cargo segment 104 including motors (not shown) used to actuate the planes 422 of the glide wings 420, and/or rudder(s) 442 of the dorsal wing(s) 440. Other substantially mechanical systems onboard the cargo segment 104 and powered by the battery bank 512 may include motors (not shown) used to actuate ballast ports 502 used to selectively receive or expel water into/out of a variable ballast tank(s) 504; an air compressor 505 used to fill a compressed air tank 506 from which air may be introduced into the variable ballast tank(s) 504 to expel water for purposes of changing buoyancy of the cargo segment 104; and a motor (not shown) used to actuate retractable and/or stowable components such as the glide wings 420 (showing starboard wing folded in FIG. 15) and/or the dorsal wing 440. The battery bank 512 also may be used to power electronic devices (e.g., actuator/ballast controls, local area networking relays, sensors) found onboard the cargo segment 104 that may be largely operated by the shipping vessel control system 320 of the lead segment 102.

Referring now to FIG. 9, a tail segment 106 may be characterized by a superstructure comprising a tail body portion 542 that may present a sharp shape to complement the substantially blunt shape of the lead segment’s 102 nose cone 202 for the purpose of reducing form drag during movement of the assembled vessel 100, particularly in submerged mode. A forward hinge mechanism 550 may be mounted to a bow of the tail body portion 542, for example, and without limitation, to facilitate mechanical attachment to a last cargo segment 104 of the assembled “train” of vessel segments 100. Similar to the lead segment 102 and cargo segment(s) 104 descriptions above, various accessories mounted on an exterior of tail segment 106 each may be configured as watertight assemblies to prevent water intrusion. For example, and without limitation, a networking cable receptacle 580 may be mounted forward on the tail body portion 542. The reconfigurable bus for delivery of electric power and/or communication signals from lead segment 102 through the “train” of cargo segments 104 to the tail segment 106 may be terminated by using the

networking cable receptacle 580 to fittedly receive the networking cable with plug 432 of the last cargo segment 104 in the assembled “train.”

The tail segment 106 may further comprise components and systems that may be deployed either partially or fully inside the tail body portion 542 of the tail segment 106. For example, and without limitation, an onboard battery bank (not shown) may be used to power various substantially mechanical systems onboard the tail segment 106 including motors (not shown) used to actuate a deployable drogue (not shown). Other substantially mechanical systems onboard the tail segment 106 and powered by the battery bank (not shown) may include ballast intake(s)/exhaust(s) (not shown) used to selectively receive or expel water into/out of a variable ballast tank(s) (not shown); an air compressor (not shown) used to fill compressed air tank (not shown) from which air may be introduced into the variable ballast tank(s) to expel water for purposes of changing buoyancy of the tail segment 106. The battery bank also may be used to power electronic devices (e.g., actuator/ballast controls, local area networking relays, sensors) found onboard the tail segment 106 that may be largely operated by the shipping vessel control system 320 of the lead segment 102.

Referring now to the schematic block diagram of FIG. 10, a variable ballast shipping vessel control system 320 is illustrated in accordance with an exemplary embodiment of the present invention. Those skilled in the art will understand that the principles of the present disclosure may be implemented on or in data communication with any type of suitably arranged device or system configured to automate submerged mode and water surface mode vessel navigation and control.

In the exemplary configuration shown in FIG. 10, the variable ballast shipping vessel control system 320 may comprise a processor 612 (also referred to herein as a “microprocessor” or “central processing unit (CPU)”) that may be operable to accept and execute computerized instructions, and also a data store 614 that may store data and instructions used by the processor 612. The processor 612 may be positioned in data communication with electrical/computing devices served by a bus that may be configured to direct input from such devices to the data store 614 for storage and subsequent retrieval. For example, and without limitation, the processor 612 may be configured in data communication with networked resources (e.g., a local area network (LAN) 630) via an underwater-capable short-range wireless interface 608 and/or via a wired data port interface 610. Using such data interfaces, processor 612 may be configured to direct input received from components of the LAN 630 to the data store 614 for storage. Similarly, the processor 612 may be configured to retrieve data from the data store 614 to be forwarded as output to various components of the LAN 630. More specifically, networked components may include each cargo segment’s onboard control devices 640 and/or the tail segment’s onboard control devices 650.

For example, and without limitation, the computerized instructions of the variable ballast shipping vessel control system 320 may be configured to implement a Navigation Subsystem 622, a Train Glide Subsystem 624, and/or a Segment Drive Subsystem 626 that may be stored in the data store 614 and retrieved by the processor 612 for execution. The Navigation Subsystem 622 may be operable to implement functionality as described below for FIG. 11 related to receipt and execution of a high-level sail plan to guide vessel navigation. The Train Glide Subsystem 624 may be operable to implement functionality as described below for FIG. 11

related to intermediate-level commands to coordinate formation and operation of a set of cargo segments configured as a “train.” The Segment Drive Subsystem 626 may be operable to implement functionality as described below for FIG. 13 related to low-level commands to manipulate the local mobility components of each segment of the “train.”

Referring now to FIG. 11, a method aspect of Navigation Subsystem 622 will now be described in detail. From the start at Block 701, configuration variables (e.g., number of cargo segments 104 employed; container identifiers and cargo weights/type for each) may be received and processed to initialize the assembled “train” (Block 710). Navigation detail then may be received/retrieved defining a delivery sortie (e.g., origin, destination, preloaded navigation maps, course outline) at Block 720. At Block 730, input sortie details may be used to calculate a detailed delivery course in the form of queued subroutines that collectively span the uninterrupted distance from sortie origin to sortie destination. For example, and without limitation, each subroutine may comprise a start waypoint and an end waypoint, between which may be defined an elemental glide maneuver for the assembled “train” (e.g., from an initial peak depth down to trough depth, and back up to a subsequent peak depth).

After a complete set of subroutines is queued and the onboard GPS detects that the “train” is at the sortie origin waypoint (Block 735), the Navigation Subsystem 622 may execute the first sortie in the queue to get underway. As shown at Block 740, the first subroutine may be a tow out subroutine which may involve moving the assembled “train” in surfaced mode (e.g., towed by one or more tugboats) out of a port of embarkation (e.g., from the sortie origin waypoint) and to a location from which the “train” may begin navigating autonomously (e.g., the next queued subroutine’s start waypoint). For the duration of the special case tow out subroutine, surfaced mode operation may entail the peak depth and trough depth settings for the entire maneuver to remain equal to the unsubmerged draft of the “train” of segments.

At Block 745, Navigation Subsystem 622 may continually monitor “train” location by GPS for the end waypoint of the tow out subroutine (also referred to herein as the “stage out” waypoint). Upon detection of stage out reached, the next subroutine in the queue may be pulled (Block 748) and executed (Block 750). This pull and execute cycle may continue until the start waypoint of a tow in subroutine (also referred to herein as the “stage in” waypoint) is detected at Block 775. Because autonomous operation of an assembled “train” as described above is based on translating synchronized variable buoyancies of the “train” segments into generally forward oscillating motion, most pulled (Block 748) and executed (Block 750) subroutines may define a respective glide maneuver comprising diving the “train” from a start waypoint at a peak depth toward a target trough depth to pick up speed; and then ascending the “train” from the achieved trough depth toward a next target peak depth to complete the elemental glide maneuver.

Special purpose subroutines may be interspersed in a delivery sortie queue to bring one or more of the “train” segments to the water surface (e.g., peak depth and/or trough depth equal to or near the unsubmerged draft) to accomplish certain surface mode operations (e.g., global positioning system (GPS) ping; satellite-based data communications; rendezvous at sea; approach to stage in). Also, in the event that sortie progress fails (e.g., the stage in waypoint is not detected within tolerance at Block 775, but the queue of subroutines is emptied at Block 748), Navigation Subsystem 622 may be configured to dynamically calculate and queue

11

one or more corrective subroutines (Block 760) and to execute these corrective subroutine(s) (Block 770) in an attempt to reach the planned stage in waypoint.

When the subroutine pull and execute cycle ultimately results in detection of the stage in waypoint (Block 775), the Navigation Subsystem 622 may execute the last subroutine in the queue (Block 780), which may be a tow in subroutine that may involve moving the assembled “train” in surfaced mode (e.g., towed by one or more tugboats) into a port of debarkation (e.g., at the sortie destination waypoint) where delivered cargo may be offloaded. For the duration of this special case tow in subroutine, surfaced mode operation may entail the peak depth and trough depth settings for the entire maneuver to be equal to the unsubmerged draft of the “train” of vessels. When, at Block 785, Navigation System 622 detects arrival at the sortie destination, shutdown protocols may be executed at Block 790 (e.g., compile operations log; capture and upload sortie debrief) before the process ends at Block 799.

Referring now to FIG. 12, a method aspect of Train Glide Subsystem 624 will now be described in detail. From the start at Block 801, configuration variables forwarded by calling Block 710 of FIG. 11 may be received and used to execute a verification test that the assembled “train” at Block 820 (e.g., configuration meets specifications; inter-segment systems operable and communicating). If an error in train assembly is detected at Block 825, control is returned to the calling Block 710 of FIG. 11 for corrective action. Confirmation of a successful verification test at Block 825 readies the Train Glide Subsystem 624 to receive and process an input subroutine.

More specifically, at Block 830, Train Glide Subsystem 624 may receive from calling Block 740 of FIG. 11 the first queued subroutine of a delivery sortie to be executed. For example, and without limitation, this first subroutine may be a tow out sequence. At Block 840, navigation components onboard the lead segment 102, cargo segment(s) 104, and/or tail segment 106 may be polled to determine real-time travel state variables (e.g., actual position, actual depth, actual heading) to be compared against the active subroutine (e.g., target position, target depth, target waypoint). If, at Block 852, an expected kickout condition (e.g., subroutine end waypoint and target depth reached) or an unexpected kickout condition is detected (e.g., subroutine trough depth exceeded), control may be returned to calling Block 740 of Navigation Subsystem 622 requesting further direction (e.g., next subroutine).

Until a kickout condition is detected at Block 852, Train Glide Subsystem 624 may loop through a series of synchronized commands to operate each of the cargo segments 104 to contribute to satisfaction of the input subroutine as a “train” assembly. For the tow out subroutine, for example, if at Block 855 the actual depth of each segment 102, 104, 106 equates to surface mode (e.g., unsubmerged draft), then all segments 102, 104, 106 may be commanded to execute neutral buoyancy (Block 860). Assuming tow out subroutine initial peak and trough are similarly set to surface mode, then detection of an actual depth above the target trough (that is, no longer in the water) may be considered impossible at Block 865. Continuing, if an actual depth below the target peak (e.g., unsubmerged draft) is detected at Block 875, then some or all segments 102, 104, 106 may be commanded to execute positive buoyancy (Block 880) to return the vessel to surface mode. During this simple tow out scenario, the assisting tugboats may be assumed to correctly direct the “train” assembly on course to the end waypoint of the tow out subroutine. In response to detecting that the “train” assembly

12

is on course (Block 889), all segments 102, 104, 106 may be commanded to execute maintain heading (Block 894), thereby cooperating with the steering actions of the assisting tugboats.

Arrival at the stage out waypoint may satisfy a kickout condition (Block 852) that prompts Navigation Subsystem 662 to begin looping through active autonomous subroutines (Block 748 at FIG. 9). At Block 830, Train Glide Subsystem 624 may receive from calling Block 740 or Block 750 of FIG. 11 the next queued subroutine of the delivery sortie to be executed. As described above, each queued subroutine may define a respective glide maneuver comprising diving the “train” from a start waypoint at a target peak depth toward a target trough depth; and then ascending the “train” from the achieved target trough depth toward a next target peak depth to complete the elemental glide maneuver. At Block 840, navigation components 555 (e.g., depth gauges, gyroscopes) onboard the lead segment 102, cargo segment(s) 104, and/or tail segment 106 may be polled to determine real-time travel state variables (e.g., actual position, actual depth, actual course) to be compared against the active subroutine (e.g., target waypoint, target trough depth, target peak depths). If, at Block 852, an expected kickout condition (e.g., subroutine end waypoint reached) or an unexpected kickout condition is detected (e.g., subroutine trough depth exceeded), control may be returned to calling Block 740 requesting further direction (e.g., next subroutine).

If at Block 855 the actual depth of each segment 102, 104, 106 matches the target depth, then all segments 102, 104, 106 may be commanded to execute neutral buoyancy (Block 860). If at Block 865 the actual depth of each segment 102, 104, 106 is above the target trough, then each of the “train” segments 102, 104, 106 may be commanded, in rolling sequence forward to aft, to execute negative buoyancy (Block 870) to accomplish the planned descent. If at Block 875 the actual depth of each segment 102, 104, 106 is below the target peak, then each of the “train” segments 102, 104, 106 may be commanded, in rolling sequence forward to aft, to execute positive buoyancy (Block 880) to accomplish the planned ascent. During all buoyancy manipulations (and particularly for descent and ascents), the actual heading of the “train” vessel may be compared against the target course for the active subroutine. If at Block 889 the target heading is determined to be on course within a set tolerance, if any, then all segments 102, 104, 106 may be commanded to execute maintain heading (Block 894). If at Block 887 the target heading is determined to be errant to port of the planned course outside a set tolerance, if any, then each of the “train” segments 102, 104, 106 may be commanded, in rolling sequence forward to aft, to execute a turn to starboard (Block 880) to tend back on course. If at Block 885 the target heading is determined to be errant to starboard of the planned course outside a set tolerance, if any, then each of the “train” segments 102, 104, 106 may be commanded, in rolling sequence forward to aft, to execute a turn to port (Block 890) to tend back on course. At Block 852, if either an expected kickout condition (e.g., subroutine end waypoint reached) or an unexpected kickout condition is detected (e.g., subroutine trough depth exceeded), control may be returned to calling Block 740 with a request for further direction (e.g., next subroutine).

Exhausting autonomous operation subroutines routinely may lead to detection of the stage in waypoint of the delivery sortie (Block 775 of FIG. 11) leading to execution of the tow in subroutine. More specifically, at Block 830, Train Glide Subsystem 624 may receive from calling Block 780 of FIG. 11 the tow in subroutine of the delivery sortie to be executed.

At Block 840, navigation components onboard the lead segment 102, cargo segment(s) 104, and/or tail segment 106 may be polled to determine real-time travel state variables (e.g., actual position, actual depth, actual course) to be compared against the tow in subroute (e.g., target waypoint, target trough depth, target peak depths). If, at Block 852, an expected kickout condition (e.g., destination reached) or an unexpected kickout condition is detected (e.g., tow in trough depth exceeded), control may be returned to calling Block 780 requesting further direction (e.g., emergency safety deployment of ballasts).

If at Block 855 the actual depth of each segment 102, 104, 106 equates to surface mode (e.g., unsubmerged draft), then all segments 102, 104, 106 may be commanded to execute neutral buoyancy (Block 860). Assuming tow in subroute initial peak and trough are similarly set to surface mode, then detection of an actual depth above the target trough may be considered impossible at Block 865. Continuing, if an actual depth below the target peak (e.g., unsubmerged draft) is detected at Block 875, then some or all segments 102, 104, 106 may be commanded to execute positive buoyancy (Block 880) to return the vessel to surface mode. During the simple tow in scenario, the assisting tugboats may be assumed to correctly direct the “train” assembly on course to the end waypoint (e.g., sortie destination) of the tow in subroute. In response to detecting that the “train” assembly is on course (Block 889), all segments 102, 104, 106 may be commanded to execute maintain heading (Block 894), thereby cooperating with the steering actions of the assisting tugboats. Arrival at the destination may satisfy a kickout condition (Block 852) that may capture and upload sortie metrics to Navigation Subsystem (Block 785 of FIG. 11) in support of execution of system shutdown protocols (Block 790 at FIG. 11) before the method ends at Block 799.

Referring now to FIG. 13, a method aspect of Segment Drive Subsystem 626 will now be described in detail. A person of skill in the art will appreciate that the independent, yet synchronized, operation of a plurality of cargo segments lends itself to simultaneous execution of multiple instances of Segment Drive Subsystem 626, including employment of multiprocessing. From the start at Block 901, a local systems power up test may be performed for each cargo segment comprising the assembled “train” (Block 901). If any of the segment’s tests throws an error, control may be returned to the calling Block 820 of FIG. 12 and, ultimately, to the calling Block 710 of FIG. 11 for corrective action. A successful set of segments tests at their respective Blocks 915 may ready each Segment Drive Subsystem 626 to receive and process an elemental glide maneuver command in support of the active subroute.

More specifically, at Block 920, Segment Drive Subsystem 626 may receive from one of the calling Blocks 890, 892, 894 of FIG. 12 a maneuver command comprising, for example, and without limitation, a buoyancy target and a turn target. If, at Block 925, the buoyancy target of the maneuver command is determined to request an ascend (e.g., positive buoyancy), then at Block 930 onboard local control devices may operate the ballast to fill with air and expel water; may operate the port plane to actuate up; may operate the starboard plane to actuate up; and may operate the dorsal rudder to remain at nominal. If instead, at Block 935, the buoyancy target of the maneuver command is determined to request a descent (e.g., negative buoyancy), then at Block 940 onboard local control devices may operate the variable ballast to fill with water and recapture (e.g., compress and store onboard) the expelled air; may operate the port plane to actuate down; may operate the starboard

plane to actuate down; and may operate the dorsal rudder to remain at nominal. If instead, at Block 945, the buoyancy target of the maneuver command is determined to request a depth hold (e.g., neutral buoyancy), then at Block 950 onboard local control devices may operate the variable ballast to remain nominal (e.g., hold steady the existing air and/or water in ballast); may operate the port plane to remain (actuate to) nominal; may operate the starboard plane to remain (actuate to) nominal; and may operate the dorsal rudder to remain at nominal.

The Segment Drive Subsystem 626 may be configured to augment any of the buoyancy actions of Blocks 930, 940, 950 with a complementary turn of the segment, in keeping with the turn target interpreted from the maneuver command. If, at Block 955, the turn target of the maneuver command is determined to request a turn to port, then at Block 960 onboard local control devices may operate the dorsal rudder to actuate to port. If instead, at Block 965, the turn target of the maneuver command is determined to request a turn to starboard, then at Block 970 onboard local control devices may operate the dorsal rudder to actuate to starboard. If instead, at Block 975, the turn target of the maneuver command is determined to request the current course be maintained, then at Block 980 onboard local control devices may operate the dorsal rudder to remain (actuate to) nominal.

A person of skill in the art will immediately recognize that an advantageous implementation of the variable ballast shipping vessel control system 320 may employ any or all of a Navigation Subsystem 622, Train Glide Subsystem 624, and/or Segment Drive Subsystem 626 collocated upon a single host computing device or distributed among two or more host computing devices. For example, and without limitation, the various components of the variable ballast shipping vessel control system 626 may be implemented in an application host/server onboard the lead segment 102. Also, for example, and without limitation, the various components of the variable ballast shipping vessel control system 626 may be implemented as redundant and concurrent executables for system reliability.

Those skilled in the art will appreciate that the present disclosure contemplates the use of computer instructions and/or systems configurations that may perform any or all of the operations involved in submersible vessel movement control. The disclosure of computer instructions that include Navigation Subsystem 622 instructions, Train Glide Subsystem 624 instructions, and/or Segment Drive Subsystem 626 instructions is not meant to be limiting in any way. Those skilled in the art will readily appreciate that stored computer instructions and/or systems configurations may be configured in any way while still accomplishing the many goals, features and advantages according to the present disclosure.

Furthermore, those skilled in the art will appreciate that auxiliary components and/or adornments may be added to the designs of the various embodiments of the present invention as described above while still accomplishing the many goals, features and advantages according to the present disclosure. For example, and without limitation, FIGS. 14, 15 and 16 illustrate additional means of reducing form drag during movement of the assembled vessel 100. Specifically, the spatial gap between the lead segment 102 and the immediately adjacent cargo segment 104 may be substantially filled by a lead slipstream cover 1002. Similarly, the respective spatial gaps between each cargo segment 104 and the immediately trailing cargo segment 104 (or, for the last cargo segment 104, the immediately trailing tail segment

15

106) may be substantially filled by a respective cargo slipstream cover 1004. As shown in FIG. 16, covering of inter-segment gaps with slipstream covers 1002, 1004 may give a variable ballast propulsion shipping vessel 100 of the present invention the "cigar" shape that is common to submarine design, but without compromising the advantageous degrees of freedom of movement between segments that facilitate variable buoyancy vessel propulsion as described hereinabove.

In some embodiments, the method or methods described above may be executed or carried out by a computing system including a tangible computer-readable storage medium, also described herein as a storage machine, that holds machine-readable instructions executable by a logic machine (i.e., a processor or programmable control device) to provide, implement, perform, and/or enact the above-described methods, processes and/or tasks. When such methods and processes are implemented, the state of the storage machine may be changed to hold different data. For example, the storage machine may include memory devices such as various hard disk drives, flash drives, CD, or DVD devices. The logic machine may execute machine-readable instructions via one or more physical information and/or logic processing devices. For example, the logic machine may be configured to execute instructions to perform tasks for a computer program. The logic machine may include one or more processors to execute the machine-readable instructions. The computing system may include a display subsystem to display a graphical user interface (GUI) or any visual element of the methods or processes described above. For example, the display subsystem, storage machine, and logic machine may be integrated such that the above method may be executed while visual elements of the disclosed system and/or method are displayed on a display screen for user consumption. The computing system may include an input subsystem that receives user input. The input subsystem may be configured to connect to and receive input from devices such as a mouse, keyboard or gaming controller. For example, a user input may indicate a request that certain task is to be executed by the computing system, such as requesting the computing system to display any of the above-described information or requesting that the user input updates or modifies existing stored information for processing. A communication subsystem may allow the methods described above to be executed or provided over a computer network. For example, the communication subsystem may be configured to enable the computing system to communicate with a plurality of personal computing devices. The communication subsystem may include wired and/or wireless communication devices to facilitate networked communication. The described methods or processes may be executed, provided, or implemented for a user or one or more computing devices via a computer-program product such as via an application programming interface (API).

Some of the illustrative aspects of the present invention may be advantageous in solving the problems herein described and other problems not discussed which are discoverable by a skilled artisan.

While the above description contains much specificity, these should not be construed as limitations on the scope of any embodiment, but as exemplifications of the presented embodiments thereof. Many other ramifications and variations are possible within the teachings of the various embodiments. While the invention has been described with reference to exemplary embodiments, it will be understood by those skilled in the art that various changes may be made and equivalents may be substituted for elements thereof

16

without departing from the scope of the invention. In addition, many modifications may be made to adapt a particular situation or material to the teachings of the invention without departing from the essential scope thereof. Therefore, it is intended that the invention not be limited to the particular embodiment disclosed as the best or only mode contemplated for carrying out this invention, but that the invention will include all embodiments falling within the scope of the appended claims. Also, in the drawings and the description, there have been disclosed exemplary embodiments of the invention and, although specific terms may have been employed, they are unless otherwise stated used in a generic and descriptive sense only and not for purposes of limitation, the scope of the invention therefore not being so limited. Moreover, the use of the terms first, second, etc. do not denote any order or importance, but rather the terms first, second, etc. are used to distinguish one element from another. Furthermore, the use of the terms a, an, etc. do not denote a limitation of quantity, but rather denote the presence of at least one of the referenced item.

Thus, the scope of the invention should be determined by the appended claims and their legal equivalents, and not by the examples given.

That which is claimed is:

1. A shipping vessel, comprising:

a train for executing underwater travel, the train formed by a plurality of segments hingedly coupled to one another in a series, each segment of the plurality of segments including one or more variable ballast tanks and one or more hydrodynamic features; and

a control system configured to:

cause the one or more variable ballast tanks of the plurality of segments to be selectively filled with and expelled of a fluid to correspondingly change buoyancies of the plurality of segments, wherein a filling of fluid into each segment causes an underwater downward acceleration of the corresponding segment and an expulsion of fluid from the segment causes an underwater upward acceleration of the corresponding segment; and

control the one or more hydrodynamic features in each segment to translate the underwater downward acceleration and the underwater upward acceleration into a desired direction as at least one of pitch and yaw such that the shipping vessel executes a glide maneuver to glide up and down underwater among the train of the plurality of segments and along a glide path defined by a series of peaks and troughs to move the shipping vessel underwater.

2. The shipping vessel of claim 1, wherein the plurality of segments further includes:

a lead segment defining a lead body portion, a nose cone, and a first aft hinge mechanism, wherein the nose cone is mounted forward of the lead body portion and a first aft hinge mechanism is mounted opposite to the nose cone;

at least one cargo segment defining a cargo body portion having a stern and a bow, a second aft hinge mechanism mounted to the stern, and a first forward hinge mechanism mounted to the bow, wherein the first forward hinge mechanism is mechanically linked in series with the first aft hinge mechanism; and

a tail segment defining a tail body portion having a bow and a second forward hinge mechanism mounted to the bow of the tail body portion, wherein the second

forward hinge mechanism is mechanically linked with the second aft hinge mechanism of the at least one cargo segment.

3. The shipping vessel of claim 2, wherein the one or more hydrodynamic features further includes:

a port and starboard glide wings projected pairedly and laterally outward from each of the lead body portion and the cargo body portion, each glide wing defines at least one plane operable in combination with the planes of the other glide wings, and at least one glide wing is stowable through at least one of retraction and folding; and

at least one dorsal wing, each having a rudder, mounted to a top of each of the lead body portion and the cargo body portion.

4. The shipping vessel of claim 1, wherein the at least one segment of the plurality of segments further includes:

a compressed air tank configured to transfer air into the one or more variable ballast tanks;

an air compressor configured to air fill the compressed air tank; and

at least one ballast intake and exhaust configured to selectively receive and expel water into and out of the at least one variable ballast tank.

5. The shipping vessel of claim 3, further includes:

a plurality of actuator motors for respectively actuating the rudders and planes; and

a battery bank configured to deliver power to at least one of the actuator motors and the control system.

6. The shipping vessel of claim 5, further includes an impeller projecting at least partly outwardly from an exterior of one or more segments of the plurality of segments, a movement of the one or more segments in submerged mode configured to be translated into a spinning of the impeller to be converted by a battery bank into electrical current for power storage into an onboard battery bank.

7. The shipping vessel of claim 1, wherein the control system is in data communication with each of the plurality of segments by at least one of: a wired interface coupled to a communications bus including a networking receptacle and a networking cable with plug; and a wireless interface.

8. The shipping vessel of claim 1, wherein at least one segment of the plurality of segments further includes a segment body and a fixed ballast mounted at a bottom of the segment body.

9. The shipping vessel of claim 8, wherein the at least one segment further includes at least one hatch positioned for top access to a cargo bay within the segment body.

10. The shipping vessel of claim 1, wherein the control system further includes a computer processor and a non-transitory computer-readable storage medium having a plurality of instructions which, when executed by the computer processor, are configured to selectively operate the at least one segments by:

receiving a subroutine including a target peak, a target trough, a target course, and a target waypoint;

operating, while polling a travel state having an actual position not equal to the target waypoint, each of the segments of the plurality of segments, by:

transmitting, upon detection of an on target condition between a target depth and an actual depth of the travel state, a set neutral buoyancy command;

transmitting, upon detection of a positive delta between the target trough and the actual depth of the travel state, a set negative buoyancy command; and

transmitting, upon detection of a negative delta between the target peak and the actual depth of the travel state, a set positive buoyancy command.

11. The shipping vessel of claim 10, wherein the control system is configured to selectively operate at least one variable ballast tank to alter a respective travel state of the at least one corresponding segment among a positive buoyancy, a negative buoyancy, and a neutral buoyancy, based on the subroutine.

10 12. The shipping vessel of claim 10, wherein, when an actual position of a travel state of a cargo segment of the train is not equal to the target waypoint, the control system is configured to operate each of the segments of the plurality of segments, by:

15 transmitting, upon detection of an on course condition between the target course and an actual heading of the travel state, a maintain heading command;

transmitting, upon detection of a port delta between the target course and the actual heading of the travel state, a starboard turn command; and

transmitting, upon detection of a starboard delta between a target course and the actual heading of the travel state, a port turn command.

20 13. The shipping vessel of claim 10, wherein the one or more hydrodynamic features further includes: a port and starboard glide wings projected pairedly and laterally outward from each of a lead body portion and a cargo body portion of the train, each glide wing defines at least one plane operable in combination with the planes of the other glide wings, and at least one glide wing is stowable through at least one of retraction and folding; and

25 at least one dorsal wing, each having a rudder, mounted to a top of each of the lead body portion and the cargo body portion; and

the control system is configured to:

operate, upon receiving the set positive buoyancy command, at least one segment of the plurality of segments by air filling the at least one variable ballast tank, pairedly articulating the planes to up position, and articulating the rudder to a laterally nominal position;

operate, upon receiving the set negative buoyancy command, the at least one segment by water filling the at least one variable ballast tank, pairedly articulating the planes to down position, and articulating the rudder to the laterally nominal position; and

operate, upon receiving the set neutral buoyancy command, the at least one segment by holding the at least one variable ballast tank, pairedly articulating the planes to vertically nominal position, and articulating the rudder to the laterally nominal position.

30 14. The shipping vessel of claim 9, each subroutine further includes a start waypoint and an end waypoint, wherein between the start waypoint and the end waypoint, an elemental glide maneuver is defined for the train from an initial peak depth down to trough depth, and back up to a subsequent peak depth.

35 15. A method for executing underwater travel, the method comprising:

using a shipping vessel including a train formed by a plurality of segments hingedly coupled to one another in a series, each segment of the plurality of segments including one or more variable ballast tanks and one or more hydrodynamic features;

causing, by a control system, the one or more variable ballast tanks of the plurality of segments to be selec-

19

tively filled with and expelled of a fluid to correspondingly change buoyancies of the plurality of segments by the control system, wherein a filling of fluid into each segment causes an underwater downward acceleration of the corresponding segment and an expulsion of fluid from the segment causes an underwater upward acceleration of the corresponding segment; and controlling, by the control system, the one or more hydrodynamic features in each segment to translate the underwater downward acceleration and the underwater upward acceleration into a desired direction as at least one of pitch and yaw by the control system, such that the shipping vessel executes a glide maneuver to glide up and down underwater among the train of the plurality of segments and along a glide path defined by a series of peaks and troughs to move the shipping vessel underwater.

16. The method of claim **15**, further includes: receiving, by the control system, a subroute including a target peak, a target trough, a target course, and a target waypoint; operating, while polling a travel state having an actual position not equal to the target waypoint, each of the segments of the plurality of segments, by: transmitting, upon detection of an on target condition between a target depth and an actual depth of the travel state, a set neutral buoyancy command; transmitting, upon detection of a positive delta between the target trough and the actual depth of the travel state, a set negative buoyancy command; and transmitting, upon detection of a negative delta between the target peak and the actual depth of the travel state, a set positive buoyancy command.

17. The method of claim **16**, further includes: operating, when an actual position of a travel state of a cargo segment of the train is not equal to the target waypoint, each of the segments of the plurality of segments by: transmitting, upon detection of an on course condition between the target course and an actual heading of the travel state for each segment, a maintain heading command; transmitting, upon detection of a port delta between the target course and the actual heading of the travel state for each segment, a starboard turn command; and

20

transmitting, upon detection of a starboard delta between the target course and the actual heading of the travel state for each segment, a port turn command.

18. The method of claim **16**, wherein the one or more hydrodynamic features further includes: a port and starboard glide wings projected pairedly and laterally outward from each of a lead body portion and a cargo body portion of the train, each glide wing defines at least one plane operable in combination with the planes of the other glide wings, and at least one glide wing is stowable through at least one of retraction and folding; and at least one dorsal wing, each having a rudder, mounted to a top of each of the lead body portion and the cargo body portion; and the method further including:

operating, upon receiving the set positive buoyancy command, at least one segment of the plurality of segments by air filling the at least one variable ballast tank, pairedly articulating the planes to up position, and articulating the rudder to a laterally nominal position;

operating, upon receiving the set negative buoyancy command, the at least one segment by water filling the at least one variable ballast tank, pairedly articulating the planes to down position, and articulating the rudder to the laterally nominal position; and

operating, upon receiving the set neutral buoyancy command, the at least one segment by holding the at least one variable ballast tank, pairedly articulating the planes to vertically nominal position, and articulating the rudder to the laterally nominal position.

19. The method of claim **16**, further includes selectively operating, by the control system, at least one variable ballast tank to alter a respective travel state of the at least one corresponding segment among a positive buoyancy, a negative buoyancy, and a neutral buoyancy, based on the subroute.

20. The method of claim **16**, further includes defining, between a start waypoint and an end waypoint of the subroute, an elemental glide maneuver for the train from an initial peak depth down to trough depth, and back up to a subsequent peak depth.
